UNITED STATES PATENT OFFICE.

DAVID HILEMAN, OF MONONGAH, WEST VIRGINIA.

DOOR-LOCK.

No. 903,857.

Specification of Letters Patent.

Patented Nov. 17, 1908.

Application filed November 16, 1907. Serial No. 402,493.

To all whom it may concern:

Be it known that I, DAVID HILEMAN, a citizen of the United States, residing at Monongah, in the county of Marion, State of 5 West Virginia, have invented certain new and useful Improvements in Door-Locks; and I do hereby declare the following to be a full, clear, and exact description of the invention, such as will enable others skilled in 10 the art to which it appertains to make and use the same.

This invention relates to door locks and latches and has for its primary object to provide a means for preventing retraction of 15 either the lock or the latch bolt.

The invention is designed principally for use in hotels and other large buildings or dwellings, and is particularly useful in this connection for the reason that guests in 20 hotels frequently lose their keys and are unable to lock their doors until a new key is furnished. Aside from this, however, the bolt holding device embodied in the lock insures further safety, as no key of any 25 description can be used to retract the lock bolt when the device is set.

In the accompanying drawings, Figure 1 is a view in elevation of a portion of a door showing the application of my lock thereto, 30 Fig. 2 is an edge view of the door and lock, Fig. 3 is a view in elevation of the device removed from the door, the casing for the latch bolt, however, being shown in section, Fig. 4 is a sectional view through the latch 35 casing showing the latch bolt in top plan, Fig. 5 is an end view of the latch casing, and, Fig. 6 is a vertical sectional view through the door of the latch bolt and its casing.

40 In the drawings, there is shown a portion of a door 10, to opposite sides of which are secured the usual plates 11 provided with key and spindle openings, as is usual. These plates also include extensions 12, which are 45 apertured, as at 13, and the purpose of these extensions and the apertures therein will be presently made apparent.

The lock proper comprises a plate 14 from one face of which extend cylindrical barrels 50 15 and 16 for the latch and lock bolts, respectively. The said barrels are each formed of a pair of semi-cylindrical sections, one section 17 of each barrel being formed integral with the plate and the other section 18 of

each barrel being adapted to be placed in position against its respective fixed section and held thereto by means of a screw 19. This screw 19, in each instance, is engaged through an ear 20 formed integral with the removable section at one end thereof and 55 having flush reception in a countersink 21 formed in the corresponding end of the fixed section. It is to be understood, of course, that these barrels are received in bores of suitable contour formed in the edge of the 60 door to which the lock is to be applied, and that by reason of the fact that the lock and latch barrels are cylindrical, mortising of the door is obviated, and that consequently 65 the door is not weakened to the extent that 70 it would be if the usual rectangular lock casing were employed.

The latch proper of the device will now be described. A block including a cylindrical portion 22 is slidably disposed in the barrel 75 15, and the said block further includes a flattened portion 23, which is of hollow construction as indicated by the numeral 24 for the reception of the usual hub 25 carried upon the usual form of spindle 26, it being 80 understood that the said spindle passes through the hollow or open portion of the block. The walls of this portion of the block are slotted, as indicated at 27, and into 85 these slots project the lugs 28 formed upon the hub 25, the slots being so restricted that when the spindle is turned, one or the other of the lugs will abut one end of one of the slots and serve to retract the block.

Formed within each of the sections of the 90 barrel 15 is a semi-circular partition 29, which has its straight edge notched, as at 30, for the passage of a latch bolt 31, which has swivel connection with the cylindrical portion of the block 22 and is provided at its 95 outer end with a beveled head 32, the latter being slidably received through a rectangular opening 33 formed in the plate 14. The head is shouldered as at 34, to limit its movement from the barrel in which it is located 100 and this shouldered portion of the head is recessed, as at 35, for the reception of one end of a spring 36 which bears at its opposite end against the partition formed in the barrel. From the foregoing description 105 of my invention it will be observed that the turning of the knob spindle will result in the retraction of the bolt against the action of

the spring, and that the bolt will return to its normal position as soon as the spindle is released, as is the case in the ordinary forms of locks now on the market.

- 5 Now in order that the bolt may be held against retraction when so desired, I have formed in the shouldered portion of the latch head a socket 37, which, when the latch bolt is in its normal position, registers with 10 the opening 13 in the upper extension 12 upon the plate 11, and I have also provided a pin 38 which is removably inserted in the said socket. It will suffice to say that the lock proper of the device includes the usual 15 form of lock bolt 38' which is likewise provided with a socket 39 for the reception of a pin 40, which is to be removably inserted therein and through the opening 13 in the lower extension 12 upon the plate 11, the 20 function of the pin being the same in either case.

What is claimed, is—

A latch comprising a cylindrical barrel formed between its ends with a partition, a bolt slideable in the barrel to one side of the 25 partition, a spring upon the stem of the bolt between the head of the bolt and the said partition, a cylindrical block slideable in the barrel to the other side of said partition, the said block being formed with a flat-sided 30 open extension, the spaced portion of the extension being slotted, a spindle, and a hub upon the spindle and working between said spaced portion of the extension, the said hub being formed with a lug which seats in said 35 slot.

In testimony whereof, I affix my signature, in presence of two witnesses.

DAVID HILEMAN.
